UNITED STATES PATENT OFFICE.

DANIEL REISER, OF CLEVELAND, OHIO, ASSIGNOR TO J. B. SAVAGE, OF CLEVELAND, OHIO.

MACHINE FOR STITCHING PAMPHLETS.

1,114,386.

Specification of Letters Patent.

Patented Oct. 20, 1914.

Continuation of applications Serial No. 466,756, filed December 10, 1908, and Serial No. 650,642, filed September 21, 1911. This application filed November 12, 1912. Serial No. 730,891.

To all whom it may concern:

Be it known that I, DANIEL REISER, a citizen of the United States, residing at Cleveland, in the county of Cuyahoga and 5 State of Ohio, have invented a certain new and useful Improvement in Machines for Stitching Pamphlets, of which the following is a full, clear, and exact description, reference being had to the accompanying 10 drawings.

This invention relates to a machine for binders' use which is adapted for the assembling, stitching, folding and backing of pamphlets, catalogues, signatures and the 15 like, the particular aspect of the invention to which this application is directed being the mechanism whereby the pamphlets, catalogues, signatures, etc. may be removed from the assembling and stitching means, 20 folded, closed tightly so that air is expelled therefrom, and deposited in a suitable receptacle.

The present application is a continuation of my former applications filed December 25 10, 1908, Serial No. 466,756 and September 21, 1911, Serial No. 650,642 respectively, reference being hereby made to each of said 30 applications as to so much of the matter disclosed and claimed therein as is common between the same and the present case.

In general it may be stated that the object of the invention is the provision of a machine whereby the stitching, folding, closing, and stacking of pamphlets, or the 35 like may be effected with a maximum of rapidity and a minimum of attention, while the more particular objects of the invention forming the subject of this divisional application are the provision of a machine for 40 the rapid, accurate, and efficient closing of books or pamphlets, the expulsion of all air contained therein so that the same may be stacked in a minimum of space; the provision of simple mechanical means whereby 45 these operations may be effected in a rapid and reliable manner; while further objects and advantages will become apparent as the description proceeds.

In the drawings accompanying and forming 50 part of this application, I have disclosed one operative means in which my inventive idea may be embodied, the same being the particular means heretofore disclosed and claimed in my prior application

filed December 10, 1908, Serial No. 466,756 55 and modified and extended in my later application, filed September 21, 1911, Serial No. 650,642.

In these drawings Figure 1 is a front elevation of the discharging end of the 60 stitching machine, showing the saddle whereon the pamphlets are carried, and the means for ejecting said pamphlets, folding and closing the same; Fig. 2 is a top plan view of the portion of the machine shown 65 in Fig. 1; Fig. 3 is a left-hand elevation of the machine; Fig. 4 is a vertical, cross-sectional view taken on the line 4—4 of Figs. 1 and 2, and looking in the direction of the arrows; Fig. 5 is a bottom plan view 70 of the discharging portion of the saddle and its associated parts; Fig. 6 is a top plan view of the stacking mechanism, the upper portion of the machine having been removed; Fig. 7 is a detail view taken on the 75 line 7—7 of Fig. 5 and showing the operating cam and reciprocating link; and Fig. 8 is a detail view showing the belt operating mechanism.

1 represents a substantially horizontal 80 feed saddle, supported on suitable standards 2—2. This saddle is substantially the shape of an inverted V, as will appear from Figs. 3 and 4, and forms a support for the books or pamphlets while the same are being carried to the stitcher (not shown), and from the stitcher to the folding and ejecting mechanism, the apex of the saddle receiving the middle portion of the open book. Carried by a bracket 3 at one end of the 85 saddle is a counter-shaft 4 upon which is mounted a pair of grooved pulleys 5—5, each of which receives one of the continuous carrier belts or tapes 6—6, the sides of the saddle being preferably broken away to 90 permit these tapes to run freely from end to end of the machine. The other end of the saddle is preferably provided with similar grooved pulleys (not shown) receiving the opposite ends of the belts or tapes, and the upper portion of each of said belts or 95 tapes projects upwardly above the surface of the saddle so that the pamphlets may come into frictional contact therewith. The direction of movement of such tapes is as 100 illustrated by the arrows in Figs. 1 and 2, whereby pamphlets, signatures, or the like, hung in open position upon the saddle at

the right-hand end of the machine, will be carried toward the left and into the folding and removing mechanism here illustrated. Located at some point between the ends of the saddle is suitable stitching mechanism, fully described in my former applications hereinbefore referred to, but not illustrated in this case, whereby stitches, staples, or other fastening means may be inserted into the backs of the booklets as they pass, while journaled in the standards 2-2 and extending parallel to the saddle 1 is a rotatable shaft 7. Mounted adjacent to the saddle 1 are suitable stop members, adapted to obstruct the passage of the books or pamphlets along the saddle, the operation of the stops being effected by means of cams carried by the shaft 7. One such stop 8 and cam 9 are illustrated in Figs. 1 and 2 hereof, although it will be understood that in practice several such stops are employed whereby the pamphlets are retarded in proper relation to the stitching mechanism to permit the staples or stitches to be attached thereto in proper position. It will also be understood that these stops perform a further function of regulating the exact time when the pamphlets shall arrive at the folding and ejecting mechanism, which is the reason that one such stop is illustrated herein.

The main power shaft 12 of the machine extends parallel with the shaft 7 and is provided with a suitable pulley 13 whereby it may be driven. Secured to the end of the shaft 7 is a sprocket wheel 14 driven by a chain 15 from a sprocket 16 carried by a gear wheel 17 which meshes with a pinion 18 carried by the shaft 12. The sprocket 16 and gear 17 are journaled upon a stud 19 carried by an arm 19, the inner end of which is journaled about the shaft 7, as shown in Fig. 3, so as to permit the use of gears 17 of different size, thereby varying the ratio of the speed of the shaft 7 to that of the shaft 12. The arm 19 is maintained in adjusted position by means of a segment 20 in a well known manner. The counter-shaft 4 is also geared to a jack shaft 21 parallel to the shaft 12, the jack shaft 21 being provided with a sprocket wheel receiving a chain 22 which in turn passes around a sprocket wheel carried by an idler shaft 23 carrying a second sprocket 24 which is connected by means of a chain 25 with a sprocket 26 carried by the main shaft 12. The idler shaft 23 is employed because of the fact that the counter shaft 4 and its pulleys 5-5 are located underneath the inverted V-shaped saddle so that direct driving is inconvenient. It will be understood, however, that many other expedients than that illustrated herein may be employed to effect such driving.

With this construction it will be understood that the main shaft 12 is continuously

driven and that the pulleys 5-5 together with their belts or tapes 6-6 are also driven at a continuous uniform speed, such speed being fixed with regard to that of the shaft 12. The shaft 7 is also constantly driven but at a speed whose relation to that of the shaft 12 can be changed by suitably choosing the size of the gear wheel 17. Accordingly it will be obvious that the tendency of the belts or tapes 6-6 is always to draw pamphlets or signatures frictionally from the right-hand toward the left hand end of the machine and will do so unless the motion of those pamphlets be arrested by means of the stops 8. Means is also preferably provided whereby the stitcher (not shown) is governed by the shaft 7 to the end that the stitcher and the stops may operate in proper relation. Whether or not this arrangement be employed, it is obvious that the last of the stops, 8, will control the arrival of the pamphlets at the folding and discharging mechanism. The mechanism for folding these pamphlets and moving them from the saddle will now be described.

Journalized in the frame work of the machine adjacent to the left hand end thereof are a pair of parallel rollers 30 and 31, said rollers being spaced from the apex of the saddle and parallel therewith. One of these rollers, as 30, is preferably mounted in slideable bearings, as shown at 32, and is yieldingly pressed toward the opposite roller, as by means of a spring 33. The other roller is positively driven from the shaft 12 by means of a chain 34 or the like. Journalized in the frame parallel with the rollers 30 and 31 are other rollers 35 and 36, and around all of these rollers are stretched a plurality of endless bands or belts 37, each of these belts passing around rollers 30, 35, and 36, and over the roller 31, as shown in Fig. 4.

Referring to Fig. 2 it will be seen that each of the rollers 35 and 36 is illustrated as a separate pulley, mounted upon a shaft of smaller diameter, although this is a matter of design and it is not essential. It will also be seen from Figs. 3 and 4 that the portion of each belt 37 between the rollers 31 and 36 is substantially parallel with the adjacent side of the saddle 1, the roller 35 being so arranged as to cause the entire belt to run without interference.

The apex of the saddle 1 is formed at the point between the rollers 30 and 31 with a longitudinal slot 40 (see Figs. 4 and 5), and mounted beneath this slot is a long, narrow knife 41 carried by the upwardly extending arms 42, said arms being integral with the lower ends of the swinging levers 43 pivoted to the frame work at 44. Secured to the shaft 7 is a cam finger 46 and connecting this cam finger with one of the arms 43 is a link 47. This link is preferably slotted at its forward end as shown at 48

48 in Fig. 7, so as to slide upon the shaft 7, being thereby supported for reciprocation relatively to that shaft. The forward end of the link is provided with a pivoted roller 49 extending across the face of the cam finger 46. At each revolution of the shaft 7, the link 47 will be advanced so as to swing forwardly the arms 43 and thrust the knife 41 upwardly through the slot 40 and thereby thrust the back of a booklet which may be thereabove into the angle between the rollers 30 and 31. The direction of rotation of the various rollers and of the belts is such as to draw the booklet upwardly and around the roller 31 and into a downwardly sloping channel defined by the guides or plates hereinafter described, and their action is of the greatest importance since they serve to press all air from between the leaves and permit the books to be packed in a minimum of space. The knife 41 is retracted by means of the spring 49.

Carried by the standards 2—2 below the saddle is a horizontal platform consisting of a pair of flat members 50—50 spaced apart as shown in Figs. 2 and 6. Each of these members is formed with a pair of transverse slots 51—51 and mounted in an upright position upon each of these members is a side board or guide 52 secured in place by means of thumb screws engaged in said slots. Secured to the inner faces of the side boards 52 are vertical guide members 53, having their upper ends bent substantially parallel with the belts 37, as shown at 54 (see Figs. 3 and 4), this portion being interposed between said belts and the saddle 1 and adapted to receive the booklets as they are discharged from the rollers 30 and 31. Carried by the inner faces of the side boards a short distance forward of the guide members 53 are other shallower guides 56, the upper ends whereof are extended to a point adjacent the roller 36 as shown in Fig. 4. Mounted between the members 50—50 is a reciprocable rod 57, the rear end whereof is articulated to a lever 58, pivoted at 59 and yieldingly held in rearward position by means of a spring 60. A link 61 connects this lever with the end of a second lever 62 pivoted at 63 and having its upper end adjacent to the shaft 7. A cam finger 64 carried by this shaft serves to oscillate said lever once at every revolution. Secured to the rod 57 is an upright plate 65, the width whereof is less than the distance between the guide members 53.

In setting up the machine, the distance between the side boards 52 is made slightly greater than the length of the pamphlet to be sewed, the distance between the guides 56 being slightly less than the length of such pamphlets. The adjustment of the cam fingers 46 and 64 is such that the plate 65 will be held in retracted position, as illus-

trated in Figs. 4 and 6, at the instant each book is ejected from the saddle and allowed to fall to the receiving platform. Immediately thereafter the plate 65 is allowed to be thrust forwardly by the spring 60, whereupon said pamphlet is flicked past the guides 56 and pressed against the rear of the pile already delivered. The guides 56 will prevent said pamphlet from falling back into the path of the succeeding pamphlets. Pawls 70 are also carried by the platform members 50 and still further prevent the return of the books ejected.

It will be apparent from the foregoing that the whole operation of the machine is regulated and controlled by the shaft 7, and that, owing to the arrangement of the stop 8 and cam 9, one pamphlet will be advanced along the saddle for each rotation of the shaft. The phase relation between the cam 9 and cam 46 is so adjusted relatively to the speed of the belts or tapes 6—6 as to permit each pamphlet to advance just a sufficient distance after its release by the stop to be brought into the proper operative relation to the knife 41. The elevation of the knife then causes the pamphlet to be caught between the rollers, whereupon the knife is retracted, the pamphlet being thereafter rolled shut. The belts 37 cause the pamphlet to be deflected around the roller 31 and directed into the chute defined between the belts 37 and guides 54 whence it falls upon the platform 50 as above described.

While I have described the use of endless belts or bands 37 in connection with the rollers 30 and 31, it will be understood that these belts or bands are of very small thickness and serve merely to direct the movement of the books or pamphlets after their removal from the saddle, but without any effect in closing or folding the same. Accordingly the operation of closing the books and removing them from the saddle would be exactly the same if these belts were omitted, excepting that these books would fall from the machine without any particular order and might even become entangled in the machine and mutilated thereby. It is also obvious that this expedient of removing and closing the pamphlets could be employed with saddles of other than V-shape, that the knife whereby the pamphlets are thrust between the closing rollers could be operated by other mechanism than that herein disclosed, that great changes could be made in the stacking mechanism, or that the same could be entirely dispensed with without interfering with the present invention, and generally that great changes in construction, arrangement, and operation of the parts could be made without departing from the scope of my inventive idea. Therefore, while I have neces-

sarily described my invention in detail and pointed out those features of construction which commend themselves to me as being most desirable, I do not propose to limit myself to the details of construction or arrangement herein described except as the same may be positively recited in the claims here-to annexed or may be rendered necessary by the prior state of the art.

10 Having thus described my invention, what I claim is:

1. The combination, with an elongated support, said support being of substantially inverted V-shape, and means for feeding books therealong, of a discharging device co-operating with said support, said device comprising a pair of rollers, one of which is located at each side of said support, a roller located at one side of one of said rollers, a belt extending around the latter roller and the further of the former rollers and over the other of said former rollers, and means for projecting between said former rollers the backs of books carried along said support.

2. The combination, with an elongated support adapted to receive books in open condition, and means for transporting the books therealong with their backs parallel to a given line, of a discharging device co-operating with said support, said device comprising a pair of rollers whose axes are parallel to said given line, a third roller located at one side of said first rollers, a belt 30 extending over the latter roller and around the further of the first rollers and past the other of said first rollers, a blade beneath said support and means for reciprocating said blade so as to project between said first 40 rollers the backs of books carried along said support.

3. The combination, with an elongated support, said support being of substantially inverted V-shape and means for conveying books therealong with backs up, said support having an elongated slot in its ridge, of a pair of rollers mounted above said support, one at each side of said slot, a blade mounted beneath the ridge of said support and adapted to be projected upwardly through the slot therein, and means for projecting said blade through said slot to engage the backs of books thereon and insert the same between said rollers.

5. The combination, with an elongated support, and means for transporting books therealong in open condition with backs up, said support being of substantially inverted V-shape and having an elongated slot 60 through and parallel with its ridge, of a roller journaled at each side of said slot, means for positively driving said rollers, a blade mounted beneath and in line with said slot, means for projecting said blades 70 through said slot at stated intervals to insert

between said rollers the backs of books conveyed along said support, and stop means associated with said support and adapted to retard the approach of books to said rollers.

5. The combination, with an elongated support of substantially V-shape and devices for feeding books longitudinally along said support, of lateral discharging mechanism co-operating with said support, and means for projecting books from said support into said mechanism, said projecting means comprising a blade, means for advancing said blade at fixed time intervals to engage the backs of books conveyed along said support, and means adapted to receive the backs of said books and press the same from the back to the forward edges thereof progressively, whereby they are folded and withdrawn from said support.

6. The combination, with an elongated support of substantially V-shape and devices for feeding books longitudinally along said support, of lateral discharging mechanism co-operating with said support, said mechanism comprising a pair of rollers and moving belts adapted to receive books from said rollers, and means for projecting books from said supports into said mechanism, said projecting means comprising a blade, and means for advancing said blade at fixed time intervals to engage the backs of books conveyed along said support and insert the same between said rollers.

7. In a device of the character described, the combination with a support for open books and means for transporting said books along said support, of a pair of parallel rollers adjacent to said support, means for inserting the backs of said books between said rollers, whereby said books may be withdrawn from said support and tightly closed, endless belts about said rollers, and a chute for receiving said books, one side of said chute being formed by said endless belts.

8. In a device of the character described, the combination with an inverted V-shape saddle and means for transporting open books along said saddle, of a pair of rollers adjacent to the ridge of said saddle, endless belts around said rollers, idle rollers for 110 said belts and serving to keep one side of the same substantially parallel with one side of said saddle, the ridge of said saddle being formed with an elongated slot between said rollers, a blade below said slot, means for inserting said blade through said slot to thrust the back of a book between said rollers, and a guide member interposed between said saddle and said belt and forming therewith a chute for the reception of said books.

9. In a device of the character described, the combination with an inverted V-shaped saddle and means for transporting open books along said saddle, of a pair of parallel rollers adjacent to the ridge of said saddle,

one at least of said rollers being yieldably supported so as to be free to move toward and from the other roller, means drawing said rollers yieldingly together, the ridge of said saddle being formed with an elongated slot between said rollers, a blade below said slot, means for inserting said blade through said slot to thrust the back of a book between said rollers, a chute for the reception

of said books, and means for rotating said rollers.

In testimony whereof, I hereunto affix my signature in the presence of two witnesses.

DANIEL REISER.
